SHOE SHINE BOX

Paul S. Mazloom, Utica, N. Y.

Application September 9, 1957, Serial No. 47,677

Term of patent 7 years

(Cl. D9—2)

Fig. 1.

Fig. 2.

Fig. 3.

Fig. 4.

I claim:

The ornamental design for a shoe shine box, as shown.
